CLAIM

We claim, the ornamental design for a confectionery, as shown and described.

DESCRIPTION

FIG. 1 is a top, left side perspective view of a confectionery, showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a rear elevation view thereof; and,

FIG. 7 is a front elevation view thereof.

The broken line disclosure forms no part of the claimed design. The dash dot lines define a boundary line between claimed and unclaimed subject matter.

1 Claim, 5 Drawing Sheets
